CLAIM

The ornamental design for an article of jewelry, as shown and described.

DESCRIPTION

FIG. 1 is a perspective view of an article of jewelry showing my new design;

FIG. 2 is a top plan view thereof, the bottom view being a mirror image;

FIG. 3 is a right side elevation view thereof, the left side being a mirror image;

FIG. 4 is an end view thereof; and,

FIG. 5 is an opposite end view thereof.

The broken lines of FIGS. 1-5 illustrate portions of the article of jewelry that form no part of the claimed design.
